UNITED STATES PATENT OFFICE.

HARRISON L. STALEY, OF RICHMOND, VIRGINIA.

TOOL FOR CLEANING HANDHOLES.

Application filed June 30, 1921. Serial No. 481,646.

To all whom it may concern:

Be it known that I, HARRISON L. STALEY, a citizen of the United States of America, and a resident of Richmond, county of Henrico, and State of Virginia, have invented certain new and useful Improvements in Tools for Cleaning Handholes, of which the following is a full and clear specification.

10 This invention has relation to that type of hand-tools adapted to clean or scrape off the gasket-seats surrounding hand-holes in boiler walls and located on the inner face of the walls, and the object of this invention is 15 to provide a simple tool adapted to operate on circular as well as non-circular handholes, as more fully hereinafter set forth.

In the drawing—

20 Fig. 1 is a view partly in side elevation and partly in section showing one way of carrying out my invention;

Fig. 2 is a vertical section on the line 2—2 of Fig. 1;

25 Fig. 3 is a plan view of the thrust devices in locked position;

Fig. 4 is a detail perspective view of the work-end of one of the tools;

30 Fig. 5 is a view similar to Fig. 2 showing a modified arrangement of the tool-bars.

35 In the drawing annexed, 10 designates a shaft affixed to the inner end of which is a circular head 11 in which are mounted four radially-movable tool-bars 12, the outer end 13 of each of which is shaped to form a cutter or scraper 13 adapted to work 40 against the gasket-seat in the boiler-wall 14, each bar being also provided with a rigid outwardly-projecting thrust-pin 15 adapted to work against the inner edge or 45 face of the hand-hole. The tool-bars are confined in radial grooves formed in the head 11 by means of a cover-plate 16 removably bolted to the outer face of the head.

50 In Figs. 1 and 2, the tool-bars are arranged radially and equidistant from each other, and each adjacent pair of bars is connected together by a bow-spring 17 lying in a chamber formed in the head 11, the ends of the spring being pivotally connected 55 to the tool-bars by pivots 18 set in recesses in the bars. The tool-bars and the springs 17 are of such length that when the thrust-pins 15 are inserted in the hand-hole, the spring will be under tension to thus hold the pins against the edge of the hand-hole so 60 that as the head is turned by the shaft 10

to cause the cutters 13 to operate on the gasket-seat, the thrust-pins 15 will follow the curvature of the hand-hole, the recession, i. e., inward movement, of each tool-bar being compensated for by a corresponding outward movement of the connected, companion, tool-bar where the hand-hole is non-circular. The equidistant arrangement of the tool-bars shown in Fig. 2 is necessary 65 where the tool is adapted for circular or elliptical holes, but for holes which are square or substantially square, the companion tool-bars should be arranged at obtuse angles to each other, as shown in Fig. 70 5, since it is always desirable that when one of the tool-bars is at the extreme inner limit of its movement, its companion tool-bar shall be at the extreme limit of its outward movement. In other words, in a tool 75 adapted for elliptical and circular holes the tool-bars will be arranged at 90° apart, whereas in the type shown in Fig. 5 the companion tool-bars should be arranged about 120° apart.

80 To hold the tool in position while it is being rotated, any suitable devices may be employed. In the present instance, I show a spider-shaped thrust-block 19 provided with feet 20 which are adapted to bear upon the outer face of the boiler-wall at points outside of the hand-hole, this special pressure-plate being loosely mounted on the shaft. Affixed to the outer end of the shaft is a 85 collar 21 and affixed to the shaft at an intermediate point is another collar 22. Slidingly mounted on the shaft between the two collars 21 and 22 is another collar 24. The sliding collar 24 is pivotally connected by a pair of toggle-links 25 and 26 to a hub 23 90 fastened to the pressure-plate 19, link 26 being provided with a handle 27. The sliding collar 24 is normally forced inwardly against the collar 22 by coil-spring 28. By swinging the handle 27 to the position shown in 100 dotted lines in Fig. 3, it will be seen that the pressure-plate 19 will be pulled back away from the tool-head and thereby permit the tool to be passed in through the hole in the boiler-wall. After the tool is positioned 105 with its cutters against the gasket-seat and its thrust-pins against the edge of the hole in the boiler-wall, the lever 27 is swung inwardly to the position shown in full lines in Fig. 3, in which position the toggle-links 110 25—26 are over center, the sliding collar 24 is pushed outwardly away from the station-

ary collar 22 and the spring 28 is put under tension. The tension of the spring 28 thrusts the pressure-plate against the outer face of the boiler-wall with a resilient pressure, thereby holding the tool-bars resiliently against the gasket-seat. It is desirable that the thrust-pins 15 shall be provided with a cutting groove 29, as shown in Fig. 4, or otherwise shaped or corrugated or serrated, so that these pins shall incidentally act to clean off the accumulation on the inner edge of the hand-hole. Inasmuch as it is desirable that the tool-head shall substantially fill the hand-hole, I have provided notches 30 in the periphery of the tool-head to receive the thrust-pins when they are at the inner extremities of their movements, thereby permitting the pins to pass within the periphery of the tool-head.

20 The nature and scope of the invention having been thus indicated and its preferred embodiment having been specifically described, what is claimed as new is:

1. A tool for the purpose set forth, embodying a shaft carrying a tool-head, said tool-head carrying two pairs of tool-bars adapted to move inwardly and outwardly with respect to the axis of the shaft, and means connecting the tool-bars to cause one of each pair to move outwardly when the other moves inwardly.

2. In a tool for the purpose set forth, a shaft carrying a tool-head, a plurality of tools carried by said head, and means for connecting the adjacent tools to cause one to move outwardly when the other is forced inwardly.

3. In a tool for the purpose set forth, a shaft carrying a tool-head, a plurality of tools carried by said head, and resilient means for connecting the adjacent tools to cause one to move outwardly when the other is forced inwardly.

4. In a tool for the purpose set forth, a shaft carrying a tool-head, a plurality of pairs of tools carried by said head adapted to move inwardly and outwardly with respect to the shaft, and compensating means connecting pairs of these tools to cause one to move outwardly when the other is forced inwardly, each of these tools being provided at its outer end with a cutter and a thrust-pin.

5. In a tool for cleaning hand-hole openings in boiler walls, comprising a shaft carrying a tool-head, a plurality of pairs of

tools carried by said head adapted to move inwardly and outwardly with respect to the shaft, and compensating means connecting pairs of these tools to cause one to move outwardly when the other is forced inwardly, each of these tools being provided at its outer end with a cutter and a thrust-pin, one or more of said thrust-pins being provided with cutting means for cleaning off the inner edge of the hand-hole.

6. In a tool for the purpose set forth, a shaft carrying a tool-head, a plurality of pairs of tools carried by said head adapted to move inwardly and outwardly with respect to the shaft, and resilient compensating means connecting pairs of these tools to cause one to move outwardly when the other is forced inwardly, each of these tools being provided at its outer end with a cutter and a thrust-pin.

7. In a tool for the purpose set forth, a shaft carrying a tool-head, a plurality of pairs of tools carried by said head adapted to move inwardly and outwardly with respect to the shaft, and bow-spring compensating means connecting pairs of these tools to cause one to move outwardly when the other is forced inwardly, each of these tools being provided at its outer end with a cutter and a thrust-pin.

8. A tool for cleaning hand-holes consisting of a shaft carrying a tool-head adapted to pass through the hand-hole, a support for the shaft and means for resiliently pressing said support against the outer face of the boiler-wall to thus draw the tools against the inner face thereof, tool-bars carried by said head adapted to slide inwardly and outwardly with respect to the shaft, said tool-bars being provided with means engaging both the inner face of the boiler-wall and the edge of the hand-hole, and resilient means in the head for causing said tools to follow the contour of the hand-hole when the head is rotated.

9. In a tool for cleaning hand-hole openings in boiler walls, comprising a shaft carrying a tool-head, a plurality of tools carried by said head, said tools having guide-pins thereon, and means acting through said tools to hold said guide-pins resiliently against the edge of the hand-hole opening.

In testimony whereof I hereunto affix my signature.

HARRISON L. STALEY.
